UNITED STATES PATENT OFFICE.

ERNEST P. LORCH, OF NEW YORK, N. Y.

POWER-SCOOP.

No. 925,817.

Specification of Letters Patent.

Patented June 22, 1909.

Application filed January 25, 1909. Serial No. 474,035.

To all whom it may concern:

Be it known that I, ERNEST P. LORCH, a citizen of the United States, and a resident of the city of New York, borough of Brooklyn, in the county of Kings and State of New York, have invented a new and Improved Power-Scoop, of which the following is a full, clear, and exact description.

This invention relates to certain improvements in power scoops, and more particularly to certain features of construction whereby the machine is rendered more efficient in its operation and whereby the material operated upon is removed from the ground and conveyed to a truck separate from the power scoop.

In the type of machines to which mine relates, a vehicle is provided with a prime mover for propelling said vehicle, and is also provided with a scoop for removing the snow or other material from the ground and delivering it to a conveyer. The conveyer is also driven by the prime mover and transports the material from the scoop to the upper portion of the machine. The material is then permitted to descend by the action of gravity to a separate truck or wagon adjacent the vehicle.

One object of my invention is to provide certain improvements whereby if the scoop in advancing should meet an obstruction, such as a projecting manhole cover or the like, it may slide backward and in doing so reach a higher level and pass over the obstruction, the scoop being immediately returned to its original position by means of a compressed elastic medium or member.

A further object of my invention is to facilitate the transferring of the material from the scoop to the conveyer, for accomplishing which object I provide a baffle wheel which may also serve to break up the material.

A further important feature of my invention resides in the chute whereby the material transferred to the conveyer may be deposited in a truck at either side of the vehicle desired, there being two separate side chutes provided, foldable to inoperative position and both of them designed to receive the material at their upper ends.

Other special features of construction and important parts of my invention will be set forth hereinafter and particularly pointed out in the claims.

Reference is to be had to the accompanying drawings, forming a part of this specification, in which similar characters of reference indicate corresponding parts in all the figures, and in which—

Figure 1 is a side elevation of a power scoop constructed in accordance with my invention; Fig. 2 is a rear view thereof, a portion of one chute being broken away; Fig. 3 is a central vertical section of the front end of the scoop, said section being taken on the line 3—3 of Fig. 4; Fig. 4 is a vertical transverse section through the scoop, said section being taken on the line 4—4 of Fig. 3; Fig. 5 is a sectional detail of a portion of the scoop; Fig. 6 is an end view of an ice-breaker, which may be employed in place of the baffle wheel shown in Figs. 1, 3 and 4; and Fig. 7 is a side elevation of the ice-breaker shown in Fig. 6.

In the specific construction illustrated in the accompanying drawings, I provide a vehicle having a main frame 10, front steering wheels 11, and rear driving wheels 12. The vehicle carries any suitable form of motor 13, for driving a shaft 14, and this shaft is connected to the rear wheels by a chain 15, and to a countershaft 16 by a chain 17. The conveyer hereinafter referred to is driven from the shaft 16, so that it will be noted that the engine operates not only to drive the vehicle, but also to drive the operating parts of my improved mechanism. The details of construction of the vehicle-driving means and connections from the motor to the conveyer may be varied at will, as the details illustrated are not considered at all important. At the front of the vehicle and between and in advance of the front wheels 11, I provide a drum 18 over which the belt 19 of the conveyer passes, and at an elevation above the frame of the vehicle and adjacent the rear end, I provide a second drum 20, also having engagement with and supporting the conveyer belt. The front drum may be supported by hangers 21, extending down from the frame 10, while the upper and rear drum 100 may be supported by any suitable form of standard 22. The two drums may be held at a definite distance from each other and the hangers 21 and the standard 22 may be braced by connecting bars 23. The conveyer belt carries a plurality of rods, plates, or flanges 24, extending transversely thereof for engaging with the material to prevent it

from sliding down the belt, the number and size of these being dependent upon the nature of the material operated upon. The detail construction of the conveyer itself constitutes no portion of my invention.

At the front end of the vehicle and slightly in advance of the drum 18, is an inclined plane constituting a scoop and made up of two separate sections 25 and 26, slidably connected together. One of these sections 25 is hinged at its rear and upper end, and at its front end it is supported upon small rollers or wheels 27, so that the relative position of the scoop in respect to the ground will not be varied by the passing of a vehicle wheel over an obstruction or into a depression in the ground or pavement over which the vehicle travels. The rear hinged end of the section 25 is on substantially the level of the axis of the drum 18, and extending downwardly from the hinged edge is a curved shield 28, concentric with the drum and serving to a certain extent as a container into which the material is deposited from the upper end of the scoop and from which the material is removed by the conveyer. The curved shield 28 serves as a housing to also protect the lower end of the conveyer. The front section 26 has its front edge adjacent the ground and its rear edge overlaps the other section 25. The two sections are slidably connected together and suitable mechanism is provided for normally holding the front section 26 in its forward or advanced position. This mechanism may include a plurality of cylinders 29 carried by the section 25 upon its under surface, and within these cylinders may be provided pistons 30 connected to piston rods 31 extending to points adjacent the undersurface of the forward section 26. The front ends of the piston rods are extended upwardly and rigidly secured to the under side of the section 26, and the cylinders in the rear of the pistons may contain any elastic material or medium under compression, for instance, compressed air. A coil spring may be used in place of the compressed air, if desired. The front edge of the section 26 travels closely adjacent the ground or pavement, so as to remove as large a quantity as possible of the snow or other material, but should this front edge strike an obstruction, as, for instance a manhole cover, or the like, the section may slide rearwardly over the upper surface of the rear section 25, and, at the same time, the section 26 will be lifted upwardly, as the front end of the section 25 is positively supported by the wheels 27. The rearward movement of the section 26 compresses the air, spring, or the like, in the cylinder 29, so that as soon as the front section passes over the obstruction, it is immediately forced forwardly and downwardly again into its normal operating position. The section 26 may be formed of a single plate, if desired,

or it may be subdivided longitudinally of the machine into a plurality of separate pieces independently connected to the section 25, so that should one piece strike an obstruction and be forced rearwardly, the remaining pieces of the section may remain in operative position, as shown particularly in Figs. 4 and 5. The section 26 is subdivided into three separate pieces and the meeting edges of the adjacent pieces are protected and concealed by strips 26^a. These strips extend longitudinally of the machine and are carried by one piece of the section and extend over a portion of the adjacent piece.

The two sections 25 and 26 are preferably so held in respect to each other that any other movement than a sliding movement is prevented, but this movement is facilitated as much as possible. For instance, the section 25 may have slots 32 extending longitudinally thereof, and the top section 26 may have depending brackets 33 extending through these slots. Each bracket may have a roller 34 disposed within the slot for engagement with the sides thereof, so as to prevent lateral movement of the upper section, and may have oppositely-disposed rollers 35 in engagement with the under side of the section 25, to prevent the upper section from being raised out of engagement with the lower section.

The front edge of the front section 26 is considerably wider than the vehicle, so that the scoop will cover a very wide path, but as the conveyer is narrower than the distance between the vehicle wheels 11, I provide the rear section 25 with side plates 36 having their front ends adjacent the side edges of the section 26 and having their rear ends converging toward the conveyer and terminating adjacent the opposite sides thereof. Intermediate the two side plates 36, I provide a rotary member for advancing the material upwardly along the upper surface of the scoop and depositing it adjacent the lower end of the conveyer. In the form shown in Figs. 1, 3 and 4, this rotary member is in the form of a drum 37, having outwardly-extending baffles 38, the drum being rotatable about an axis substantially parallel to the axis of the drum 18. The baffle wheel is rotated in the reverse direction to the drum 18, that is, its under side travels rearwardly, whereas, the under side of the drum 18 travels forwardly. For driving the drum 37 from the drum 18, I may provide any suitable mechanism, for instance, a crossed belt 39. Instead of making the baffles 38 continuous throughout the length of the body of the rotary member, I may subdivide them into sections and utilize the rotary member as a pick or breaker for subdividing the material. As shown in Figs. 6 and 7, I provide the drum 37 with a plurality of outwardly-curved and pointed baffles or

teeth 38*, which serve to break up and subdivide any large pieces of ice or frozen snow, which might tend to injure the conveyer were they directly delivered thereto.

5 The material upon being delivered to the conveyer is moved upwardly along with the latter and is prevented from slipping off the edges of the conveyer by any suitable means as, for instance, side bars 40. At the upper 10 end of the conveyer I provide a receiver 41 into which the material is deposited and from which it may be delivered to a wagon or truck at the side of the vehicle. The under side or floor of the receiver is formed 15 of two sections 42, 42, inclined in opposite directions and adjacent the lower and outer edges of these floor sections are pivotally connected two chutes 43, 43. Each chute extends outwardly at an angle to the receiver and terminates at a distance from the side of the vehicle and at such an elevation that a truck or cart 44 may be drawn along 20 at the side of the vehicle and beneath the end of the chute to receive the material delivered therethrough. Each chute is preferably hinged at its upper end and is supported at 25 its lower end by a movable brace or bracket 45, so that the chute may be held outwardly in its operative position or may be swung 30 downwardly into engagement with the side of the vehicle, as indicated in dotted lines at the left-hand side of Fig. 2. Each chute at its outer end is provided with a damper, 35 valve or controller for preventing the material from passing therethrough, said damper valve or controller being preferably in the form of a curved plate 46, movable transversely of the chute through a slot in the top thereof and supported by arms 47 pivoted to the sides of the chute.

Within the receiver 41 and pivoted at the intersection of the two inclined bottom sections 42, is a partition 48, subdividing the receiver into two separate compartments. 45 This partition may extend upwardly, as indicated in Fig. 2, so that the material will be deposited in the receiver in approximately equal quantities upon opposite sides and be delivered to both of the chutes, or the partition 50 may be swung in either direction until its upper edge comes adjacent the side wall of the receiver and the partition lies substantially in alinement with the opposite floor section 42. With the partition in one of its 55 limiting positions, all of the material delivered to the receiver will go to one of the chutes, while with the partition in the opposite limiting position, all of the material will be conducted to the opposite chute. 60 For controlling the position of the partition, the latter is preferably provided with a downwardly-extending arm 49, intermediate the two floor sections 42, and a cord 50 is connected to the lower end of this arm and extends over two pulleys 51. By pulling down 65

one end of the cord, the partition may be swung toward the opposite side of the receiver.

Having thus described my invention, I claim as new and desire to secure by Letters 70 Patent:

1. A machine of the class described, comprising a vehicle and a scoop or shovel adjacent the front end thereof, said scoop or shovel being formed of two overlapping sections 75 slidably connected together, and means for raising the forward section upon the rearward movement thereof.

2. A machine of the class described, comprising a motor vehicle, a scoop or shovel 80 carried thereby and having two overlapping sections slidably connected together, means for resiliently holding one of said sections in its advanced position, and means whereby said section is raised upon the rearward 85 movement thereof.

3. A machine of the class described, including a vehicle having a scoop or shovel at the front end thereof, said scoop or shovel comprising two sections 90 slidably connected together, one of said sections having its rear end pivotally connected to the vehicle, rollers or wheels for supporting the forward end of said section, and means carried by said last-mentioned section for resiliently holding the 95 other section in advanced position with the front edge thereof adjacent the ground.

4. A scoop or shovel formed of two sections 100 slidably connected together, means for pivotally supporting the rear edge of one section, wheels for supporting the forward end of said last-mentioned section, a cylinder carried by said section upon the under side thereof, a piston within said cylinder, and a piston rod secured to said piston and to the 105 under side of the other section for resiliently holding the latter in its advanced position.

5. A scoop or shovel including two inclined sections, means for supporting one of said sections, means for connecting the two 110 sections to permit of a relative sliding movement, and resilient means connecting said sections for holding the two sections in one limiting position and permitting of the rearward and upward movement of one section 115 upon the engagement of said section with an obstruction.

6. A machine of the class described, including an inclined conveyer, a scoop adjacent the front lower end of the conveyer and 120 having one edge thereof adjacent the ground, and a rotatable member adjacent the upper surface of said scoop for removing the material therefrom and transferring it to said conveyer.

7. A machine of the class described, including a vehicle, a drum supported adjacent the front end thereof, an endless conveyer movable over said drum, a scoop adjacent said drum and having one edge thereof adja- 130

1 cent the ground; a baffle wheel adjacent the upper surface of said scoop, and means for rotating said wheel in the opposite direction to the direction of rotation of the drum to 5 transfer material from the scoop to the lower end of the conveyer.

8. A machine of the class described, including a vehicle, a drum supported adjacent the front end thereof, an endless conveyer 10 movable over said drum, a scoop adjacent said drum and having one edge thereof adjacent the ground, a baffle wheel adjacent the upper surface of said scoop, and means for rotating said wheel in the opposite direction to the direction of rotation of the drum to 15 transfer material from the scoop to the lower end of the conveyer, said wheel also operating to break up or subdivide the material in the scoop.

20 9. A device of the class described, comprising a vehicle having a scoop at the forward end thereof, an inclined conveyer for conducting the material from the scoop to the upper rear portion of the vehicle, a receiver 25 for said material, and oppositely-disposed

downwardly-inclined chutes connected to the sides of said receiver for directing the material out of the receiver at either side thereof, each of said chutes being pivotally connected to the receiver and movable to a position adjacent the body of the machine. 30

10. A device of the class described, comprising a vehicle having a scoop at the forward end thereof, an inclined conveyer for conducting the material from the scoop to 35 the upper rear portion of the vehicle, a receiver for said material, and oppositely-disposed downwardly-inclined chutes connected to the sides of said receiver for directing the material out of the receiver at either side 40 thereof, each of said chutes having a valve or gate at the outer end thereof for controlling the flow of material therethrough.

In testimony whereof I have signed my name to this specification in the presence of 45 two subscribing witnesses.
